ELECTRICAL TURNING GEAR FOR STARTING INTERNAL COMBUSTION ENGINES

Filed Jan. 16, 1929

FIG. 1.

FIG. 2.

INVENTOR.

Frederick H. Royce

BY Cannaaly Bros

ATTORNEY.

UNITED STATES PATENT OFFICE

FREDERICK HENRY ROYCE, OF WEST WITTERING, NEAR CHICHESTER, ENGLAND, AS
SIGNOR TO ROLLS ROYCE LIMITED, OF DERBY, ENGLAND

ELECTRICAL TURNING GEAR FOR STARTING INTERNAL-COMBUSTION ENGINES

Application filed January 16, 1929, Serial No. 332,970, and in Great Britain February 14, 1928.

This invention has reference to electric turning gear for starting internal combustion engines, of the type in which a pinion fixed for rotation on an extension of the armature shaft of the starting motor, is caused to move axially into engagement with a toothed wheel geared to the engine shaft. 5

In turning gear of the type referred to as heretofore made, the pinion has been arranged in its normal (i. e. out of engagement) position either more remote from, or nearer to, the motor than the toothed wheel with which it engages.

The latter arrangement is often desirable 15 to meet the exigencies of design of the engine, but has a comparative disadvantage, in that the over-hang or extended part of the shaft beyond its adjacent bearing, is at its maximum when the instrument is working, 20 thus throwing a great bending strain on the shaft and heavily loading the bearings.

The object of this invention is to eliminate 25 or minimize this disadvantage and to make other constructional improvements.

According to this invention the relative 30 diameter of the shaft, and the bearing in the end boss of the motor casing adjacent the pinion on the one hand, and of the pinion on the other hand, are such that the pinion (following the axial movement of the shaft) can be made to recede (when in its normal position) into the hollow of the bearing.

An example of this invention is illustrated 35 in the accompanying drawings.

Fig. 1 shows a sectional elevation of the 40 starter motor, and Fig. 2 a portion of Fig. 1, to an enlarged scale.

a is a bracket forming part of the engine 45 crankshaft case, *a*¹ the case containing the starter connected to such bracket, *a*² an end cover of the case of the starter, *a*³ a flanged sleeve and *a*⁴ a bearing bush, *b* are poles of the starter motor, *b*¹ the field windings, *b*² is the armature and *b*³ the commutator, *c* is the 50 shaft of the motor having an enlarged part *c*¹ rotating in the bearing bush *a*⁴, and *c*² is the pinion rigidly mounted on the shaft (for rotation) of the smaller diameter than the enlarged part *c*¹. *d* is the fly wheel of the engine. 55

With apparatus as described the fly-wheel can be arranged in close proximity to the end of the motor and when the pinion is engaged therewith such pinion is in close proximity to the adjacent bearing of the shaft. 60

What I claim is:—

1. Electric turning gear for starting internal combustion engines of the type in which a pinion fixed for rotation on an extension of the armature shaft of a starting motor is 65 caused to move axially into engagement with a toothed wheel geared to the engine shaft, characterized in that normally the pinion is within the hollow of the end bearing of the motor shaft. 70

2. Electric turning gear as claimed in 75 claim No. 1, the bearing of the motor shaft adjacent to the pinion and the part of the shaft rotating in such bearing being respectively of larger diameter than the pinion. 80

In testimony whereof I have hereunto affixed my signature.

FREDERICK HENRY ROYCE.
